ELECTRICALLY HEATED LUNCH BOX

Daniel L. Macha, 3119 Moor Drive,
Nederland, Tex. 77627

Filed Dec. 30, 1974, Ser. No. 537,553

Term of patent 14 years

Int. Cl. D3—01

U.S. Cl. D7—76

FIG. 1

FIG. 2

FIG. 3

FIG. 4

FIG. 1 is a front perspective view of an electrically heated lunch box showing my new design;

FIG. 2 is a side elevational view as seen from the left of FIG. 1;

FIG. 3 is a rear elevational view thereof; and

FIG. 4 is a top plan view thereof.

The bottom of the design is flat and unornamented. I claim:

The ornamental design for an electrically heated lunch box, as shown and described.
